CLAIM

The ornamental design for a biological sample analysis system, as shown and described.

DESCRIPTION

FIG. 1 is a front view of a biological sample analysis system; FIG. 2 is a back view of the biological sample analysis system;

FIG. 3 is a side view of the biological sample analysis system; FIG. 4 is a side view of the biological sample analysis system; FIG. 5 is a top view of the biological sample analysis system; FIG. 6 is a bottom view of the biological sample analysis system;

FIG. 7 is a top, front, and side perspective view of the biological sample analysis system; and,

FIG. 8 is a front, side, and bottom perspective view of the biological sample analysis system.
